UNITED STATES PATENT OFFICE

160,752

MATTRESS COVER OR SIMILAR ARTICLE

Ben Turner, Bellrose, and Milton Forster and Emanuel Forster, Brooklyn, N. Y.

Application March 26, 1949, Serial No. 1,632

Term of patent 3½ years

(Cl. D92—2)

To all whom it may concern:

Be it known that Ben Turner, Milton Forster, and Emanuel Forster, citizens of the United States of America, residing in Bellrose, county of Queens, and State of New York; Brooklyn, county of Kings, and State of New York; and Brooklyn, county of Kings, and State of New York, respectively, have invented a new, original, and ornamental Design for a Mattress Cover or Similar Article, of which the following is a specification, reference being had to the accompanying drawing, forming part thereof.

We claim:

The ornamental design for a mattress cover or similar article, substantially as shown.

BEN TURNER.
MILTON FORSTER.
EMANUEL FORSTER.
